UNITED STATES PATENT OFFICE.

ALPHONSE BAZIN, OF SWAMPSCOTT, MASSACHUSETTS.

NUT-LOCK.

1,088,515.

Specification of Letters Patent. Patented Feb. 24, 1914.

Application filed July 2, 1913. Serial No. 777,107.

To all whom it may concern:

Be it known that I, ALPHONSE BAZIN, a German citizen of the United States, residing at Swampscott, in the county of Essex and State of Massachusetts, have invented new and useful Improvements in Nut-Locks, of which the following is a specification.

This invention relates to improvements in locking devices by which a nut is held from turning or jarring loose from a bolt to which it is applied, and the improvement resides in the construction, combination and arrangement of parts set forth in the following specification and falling within the scope of the appended claim.

In the accompanying drawings: Figure 1 is a front elevation illustrating my improved lock in engaging position upon a nut, Fig. 2 is a sectional view on the line 2—2 of Fig. 1, 20 Fig. 3 is a view illustrating the manner in which the locking device may be removed from the nut without necessitating the entire removal of the retaining screws, and Fig. 4 is a perspective view of the improvement.

In the accompanying drawings, the numeral 1 designates a bolt, 2 a nut and 3 my improved locking plate. The plate embodies what may be termed a rounded head 30 4, which is formed with a polygonal opening, and the walls provided by the opening are formed with depressions or notches 5, whereby the plate may be arranged upon various sizes and shapes of nuts. The plate 35 3 is constructed from a flat strip of resilient material and its portion extending from its head 4 is formed with a depression 6 which is centrally provided with a slot 7, the said slot opening at one side of the plate 3. 40 Adapted to be received within the depression 6 is a headed screw 8, the threaded shank of the screw passing between the walls formed by the slots 7 so as to permit of its head tightly compressing against the inner 45 wall formed by the depression 6. It will be noted that the depression is arranged concentric of the bolt 1, and that its opposite end walls are rounded, the end walls ar-

ranged adjacent the entrance of the slot 7 being intersected by the said slot, and the 50 said ends contact with the head to prevent the plate being accidentally removed from the nut. However, when it is desired to remove the plate without removing the screw 8, the screw may be loosened sufficient to 55 raise its head above the depression 6 and the plate may then be turned upon and with the nut to the position illustrated in Fig. 3, and an outward movement of the plate will 60 remove the same from the nut. The plate 65 may be employed in lieu of a wrench for removing the nut from the bolt, in which instance the screw 8 is entirely withdrawn, and the plate, still engaging with the nut, is rotated in an unscrewing direction, and 70 to facilitate such removal of the nut by the plate, any instrument such as an ordinary nail punch or the like may be inserted within the slot 7 to contact with the inner wall of the said slot, the said instrument thus serving as a handle for the plate.

Having thus described the invention, what I claim is:

In combination with a bolt and a nut therefor, of a locking plate, said locking 75 plate including a head having a polygonal opening, the inner edges of which are formed with substantially V-shaped notches, the plate below its head being formed with a rounded depression and the said depressed 80 portion being centrally provided with a slot which enters the depression from one of the side edges of the plate, the depression having its end walls rounded, and one of the 85 said walls being interrupted by the slot, and a headed threaded member passing between the walls of the slot and engaging with the wall of the depression, substantially as and for the purpose set forth.

In testimony whereof I affix my signature 90 in presence of two witnesses.

ALPHONSE BAZIN.

Witnesses:

FRED D. BLANCHARD,
HERBERT J. CARY.
